TENSIONING JACK

Manfred E. A. Wyder, 18719 Del Bonita,
Rowland Heights, Calif. 91748

Filed Nov. 29, 1972, Ser. No. 310,591

Term of patent 7 years

Int. Cl. D8—05

U.S. Cl. D8—51

FIG. 1 is a perspective view of a tensioning jack showing my new design;

FIG. 2 is an elevational view of the tensioning jack showing the side thereof not shown in FIG. 1;

FIG. 3 is an end view of the rod-receiving end of the tensioning jack, the top end as shown in FIG. 1;

FIG. 4 is an edge elevational view of the tensioning jack showing the edge thereof not shown in FIG. 1; and

FIG. 5 is an end view of the tensioning jack showing the end that is the lower end in FIG. 1.

I claim:

The ornamental design for a tensioning jack, substantially as shown.
